COOKING RANGE

Jesse W. Barker, Geneva, N. Y.

Application May 11, 1935, Serial No. 21,037

2 Claims. (Cl. 126—1)

This invention relates to improvements in cooking ranges and more particularly to coal and wood ranges and combination coal, wood and gas ranges.

One of the difficulties encountered in connection with the manufacture of enameled stoves, of the above type, is the fact that when certain of the parts, such as the lower contacting edges of the side walls and front frame and the top edge of the main bottom of the range, become cracked and chipped, it has been difficult to replace such damaged parts without practically dismantling the entire stove.

Another objection has been the labor and expense involved in replacing the oven bottoms which frequently became broken.

The general object of the present invention is to overcome the foregoing objections by extending the lower ends of the front frame and side walls or panels to cover the sides and front of the main bottom of the range, and by so mounting the oven bottom that the latter can be readily removed.

Other objects and advantages of the invention will be understood as the specification is considered in connection with the accompanying drawings, in which:

Figure 1 is an exploded view showing the various parts of the stove body including side and rear walls, and front frame, also the main oven bottom and front and side panels of the oven;

Figure 2 is a fragmentary front view partly in section of the front frame showing the main bottom of the stove and the oven bottom in place above the main bottom, one side wall of the oven being also shown;

Figure 3 is a section on the line 3—3 of Figure 2;

Figure 4 is a vertical sectional fragmentary view showing the relationship between the main oven bottom, the front frame, the front panel and one of the legs of the stove; and

Figure 5 is a sectional fragmentary view through the side walls of the oven and the oven bottom showing the manner in which the oven bottom is supported on the ledges of the side walls.

Referring more particularly to the drawings, 1 denotes a coal and wood or combination coal, 50 wood or gas range body comprising a main rectangular bottom 2, side walls 3 and 4, a rear main wall 5 and a front frame 6. The main bottom 2 of the range is formed with a flange 7 depending from a flat rectangular top face or bottom 8. 55 This flange, is slightly offset with respect to the

top portion 8 to provide a shoulder 9, for a purpose presently described.

The side walls 3 and 4 and the front frame 6 are formed with similar depending vertical flanges 10, 11 and 12 respectively which extend down over 5 and conceal the two side faces and the front face of the flange 7 depending from the main bottom 2, and are formed with inwardly extending horizontally disposed flanges 13, 14 and 15, on the respective side walls and front frame, which seat 10 upon the shoulder 9, when the parts are thus assembled. At the rear of the range main back wall 5 is formed with a depending flange 17, which conceals the rear face of the flange 7. The lower edge of the flange 7 of the main bottom 15 rests upon supporting lugs of usual construction (not shown) with which each leg 19 is provided.

The side walls 3 and 4 of the stove and front frame 6 are secured to the main bottom 2 by 20 means of bolts 20. Thus the flange 7 is provided with bolt holes 21 which register with holes 22 in the depending flanges of the side walls and front frame. Nuts 23, serve the purpose of securing the bolts in place.

A front base strip or plate 24 and two side base strips 25, only one of which is shown, respectively cover and conceal the depending vertical flanges of the side walls and front frame, thus eliminating the necessity of enameling these parts as well 30 as the flange of the main bottom. Adjacent strips are secured together through the medium of the legs 19, to which they are bolted.

Access to the coal burner box part of the stove is had through an opening 27 in the front frame, 35 and an opening 28 in the frame provides access to the oven compartment 29. The oven space is enclosed at its sides and rear by oven side panels or walls 30 and 31 and the main back wall 5 respectively. An oven bottom or plate 32 removably closes the bottom of the oven. This bottom or plate is supported at its sides upon ledges 33 formed on the oven side panels, and at its rear end rests upon a stepped portion or shoulder 34 formed on the main back of the range. The 45 forward edge of the plate 32 is formed with a reduced extension or lip 35 which engages or hooks beneath a corresponding flange or shoulder 36 on the jamb of the front frame 6. The space between the oven bottom plate 32 and the main bottom 2 of the range constitutes a clean out space 37 to which access may be had through an opening 38 in the front frame. Bolts 39 extending downwardly through the flue securely fasten the plate 32 to the main bottom.

If the oven bottom or plate becomes cracked or otherwise damaged, as frequently happens, or should it become necessary to repair the flue, the oven bottom can readily be taken out after unscrewing the nuts 40 from the bolts 39 and removing the latter. The oven bottom plate can then be lifted up from its seat on the ledges 33 and the shoulder 34, it of course being necessary to tilt the oven bottom so that the lip 35 can be disengaged from beneath the rearwardly extending flange or shoulder 36 on the front frame.

It will of course be understood that closure members (not shown) will be provided for the door openings 27 and 28.

Having thus described my invention, what I claim is:

1. In a range, a body comprising a main bottom, side walls and a rear wall and a front frame enclosing said main bottom, an oven within said side walls and front frame having side walls spaced from the first mentioned side walls and supported by said main bottom, said front frame having an inwardly projecting flange and the rear wall having a shoulder, said side oven walls hav-

ing flanges, an oven bottom adapted to engage beneath said flange at its forward edge and to seat on said wall flanges and on said shoulder at its rear edge in spaced relation to the main bottom, and detachable means carried by the main bottom and holding said oven bottom in its proper position. 5

2. In a range, a body comprising a main bottom, side walls and a rear wall and a front frame, 10 an oven within said side walls, and front frame 10 and having side walls spaced from the first mentioned side walls and supported by the main bottom, and said oven walls having inwardly extending flanges, said front frame having an inwardly projecting flange and the rear wall having a 15 shoulder, an oven bottom adapted to engage beneath said flange at its forward edge and to rest on the inwardly extending flanges of the side walls of the oven, spacing it from the main bottom, and detachable means carried by the main 20 bottom and holding said oven bottom in its proper position.

J. W. BARKER.
